(No Model.)

L. D. DAVIS.
TUBULOUS STEAM BOILER.

No. 571,650.

Patented Nov. 17, 1896.

UNITED STATES PATENT OFFICE.

LEONARD D. DAVIS, OF ERIE, PENNSYLVANIA.

TUBULOUS STEAM-BOILER.

SPECIFICATION forming part of Letters Patent No. 571,650, dated November 17, 1896.

Application filed November 26, 1895. Serial No. 570,202. (No model.)

To all whom it may concern:

Be it known that I, LEONARD D. DAVIS, a citizen of the United States, residing at the city of Erie, in the county of Erie and State of Pennsylvania, have invented certain new and useful Improvements in Tubulous Steam-Boilers; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to certain new and useful improvements in tubulous steam-boilers; and it consists, primarily, in constructing the boiler with headers, in which are secured tiers of inclined water-tubes which form the upper and lower walls of return fire-flues, and with downflow-pipes so connecting the headers that there is a well defined and positive circulation of the water in the boiler and of the heat and products of combustion through the fire-flues formed by said tiers of water-tubes from the rear to the front of the boiler in direct contact with every portion of the heating-surface thereof.

Another feature of my invention consists in constructing the headers of the boiler in sections, so that each front and rear section of the headers has secured therein one tier of water-tubes and a downflow-pipe at each side thereof, the front header-sections being secured together one upon the other and the rear header-sections simply resting one upon the other, whereby the tier of water-tubes and the downflow-pipes between each front and rear sections are free to expand and contract without interfering with the others.

Another feature of my invention consists in inserting the feed-water pipes some distance into the front end of each of the lowermost downflow-pipes, so that the cold feed-water is heated in its passage through these downflow-pipes toward the rear of the boiler.

Another feature of this invention consists in making the water-tubes forming the tiers connecting the header-sections either with a longitudinal rib on each side, so that when the tubes are secured in the headers these ribs overlap each other and form practically a fire-

tight joint, or by making the water-tubes of plain tubing, with the ends thereof swaged down sufficiently so that they can be secured 55 in the headers with the sides thereof in contact with each other, and then sealing the joints below them by stretching asbestos cords over each joint, so as to form substantially fire-tight joints between these tubes. 60

Other features of my invention are set forth hereinafter in the specification and claims.

In the accompanying drawings, Figure 1 is a front view in elevation of my improved tubulous steam-boiler. Fig. 2 is a longitudinal vertical section of the same on the line $x-x$ in Fig. 1, looking in the direction of the arrow. Fig. 3 is a rear end view of the same, partially in elevation and partially in section, on the line $z-z$ in Fig. 2, looking in the direction of 70 the arrow. Fig. 4 is a transverse vertical section of the same on the line $y-y$ in Fig. 2, looking in the direction of the arrow. Fig. 5 shows a view in detail of a section of one of the headers with water-tubes having longitudinal ribs on the sides thereof overlapping each other, so as to seal the joint between them. Fig. 6 shows a top or plan view of the detail view shown in Fig. 5. Fig. 7 shows a view in detail of a section of one of the headers with water-tubes therein, illustrating another method of sealing the joint between the water-tubes. Fig. 8 shows a top or plan view of the detail view shown in Fig. 7. 80

In the construction of my improved tubulous steam-boiler illustrated in the accompanying drawings the front header of the boiler is constructed of sections, each consisting of a transverse oblong shell A, inclined upward from the center thereof to the sides of the 90 boiler, where it joins vertical cylinders A' A', these cylinders A' being provided with flanges a, through which bolts a' are placed, by means whereof they can be bolted together. Upon the upper of these cylinders A' A' is secured 95 a steam-drum B, so that when the cylinders A' A' are bolted together they form vertical passages from the ends of the shells A up into the steam-drum B. The rear header of the boiler is also constructed of sections, each 100 consisting of a transverse oblong shell D, inclined upward from the center thereof to the sides of the boiler, where it joins vertical cylinders D' D', these cylinders D' being each

provided with closed heads d d' , so that there is no communication upward from one to the other, but they simply rest one upon the other. To the lowermost of the header-cylinders D D' are secured downwardly-projecting pipes C C , which communicate with a mud-drum C' , provided with a blow-off pipe c .

Between each oblong shell A at the front end and the corresponding shell D at the rear end of the boiler I secure a tier of straight water-tubes E . These tubes E , I make, preferably, with longitudinal ribs e on their sides, as illustrated in Figs. 5 and 6, which ribs overlap when the tubes are secured in the shells A and D of the headers, so as to form practically fire-tight joints between the tubes. These ribbed tubes enable me to secure their ends in openings in the header-shells A and D by expanding them therein in the usual manner, access being had thereto through screw-plugged openings a^2 and d^2 in the outer edges of the header-shells A and D , opposite the openings therein, in which the ends of the tubes E are secured. In securing these ribbed tubes in place in the header-shells A and D , I cut away the ribs e thereon for a sufficient distance at each end thereof, so that the end of the tube will pass into the openings in the shells a sufficient distance to permit the insertion or removal of any one or more tubes by loosening them and then moving them longitudinally when desired.

To close the openings between the ends of the tubes where the flanges e are cut away, I secure to the header-shells A and D angle-irons e' , as illustrated in Figs. 5 and 6. I can, however, use ordinary tubing for the tiers of water-tubes. In this case I swage the ends of the tubes down, as illustrated in Fig. 8, to a small enough size, so that when they are secured by expanding them in the openings in the header-shells the sides of the tubes will contact with each other, as illustrated in Figs. 1, 4, 7, and 8 of the drawings.

To make the joints between the tubes fire-tight, I draw the ends of asbestos cords e^2 through between the openings formed by the swaged ends of the tubes E and stretch them along the upper sides of the joints between the tubes, as illustrated in Figs. 7 and 8. I, however, prefer the ribbed tube construction hereinbefore described. Each front header-section A A' is also connected to its corresponding header-section D D' at the rear of the boiler by means of two downflow-pipes F F , connecting the cylindrical portions A' and E' of each of the header-sections together at each side of the boiler, these pipes F F being sufficiently large to convey the water passing upward through the corresponding tier of water-tubes from the front to the rear of the boiler.

The headers A A' and D D' when put together to form the boiler are arranged one above the other, as illustrated in the drawings, the front header-sections A A' being

firmly secured together by means of flanges a and bolts a' , and the rear header-sections simply rest one upon the other, and when thus placed together the tiers of tubes E incline upward from the rear toward the front of the boiler at an angle of, say, from fifteen to twenty degrees, and form, together with the header-shells A and D , the upper and lower walls of inclined fire-flues E' , the side walls of these flues being formed by vertical fire-walls G , which form the sides of the firebox H and flue H' , and extend up between the downflow-pipes F F and the outer tubes E of the tiers of water-tubes and also form the sides of the flues E' , as illustrated in Figs. 2 and 4, so as to prevent any excessive heating of the downflow-pipes F F , the fire and products of combustion passing from the firebox H along the flue H' into the combustion-chamber H^2 at the rear of the boiler and thence back through the inclined fire-flues E' to the front of the boiler and out through the smokestack-opening B' . It will be observed that by this construction that each header-section D D' at the rear of the boiler is free to respond to the longitudinal expansion and contraction of the water-tubes E and downflow-pipes F F , secured therein, without regard to the expansion and contraction of the water-tubes and downflow-pipes in the other header-sections, so that any undue strain upon the tubes and headers is thereby avoided. The feed-water is introduced into the boiler through pipes I I , which enter the cylindrical portions A' A' of the lower front header-section and extend rearwardly into the lower downflow-pipes F , connecting this header-section with the cylindrical portions D' D' of the lower rear header-section, and the feed-water as it passes rearwardly through said lowermost downflow-pipes F F in contact with the hot water therein becomes separated from the impurities thereof, and these impurities being heavier than the water are precipitated and pass down through the pipes C into the mud-drum C' , where they can be blown off through blow-off pipes c therein, the feed-water thus purified passing on through the parts D' D' into the shell D of the rear header, and thence back to the front of the boiler through the lowermost tier of water-tubes E , and thence back through the second pair of downflow-pipes F F to the second header-section D' D , and again back to the front through the second tier of water-tubes E until it, together with the steam generated, reaches the steam-drum B through the passage formed by the cylindrical portions A' A' of the header-sections at the front of the boiler, the surplus water meanwhile passing down through the cylindrical passages A' A' of the front header to the downflow-pipes F F to repeat its traverse back and forth until it is reduced to steam.

In the outer sides of the cylindrical parts D' of each rear header-sections D D' , I pref-

erably place hand-holes D², so that access may be easily had to the header-sections to clean them when desired.

In the drawings and the foregoing description I have illustrated and described a convenient construction of my invention; but it is obvious that many portions thereof may be modified in their construction without departing from the spirit and intent of my invention. Therefore I do not limit myself to the exact construction herein shown and described; but

What I claim as new, and desire to secure by Letters Patent of the United States, is—

15 1. The combination in a tubulous steam-boiler, of front and rear headers having openings therethrough for the passage of the products of combustion, and water-tubes secured in said headers in close proximity to each other, so as to form with the openings in the headers substantially fire-tight fire-flue walls, substantially as and for the purpose set forth.

20 2. The combination in a tubulous steam-boiler, of a front header consisting substantially of transverse sections, having openings between them for the passage of the products of combustion, and vertical ends on said transverse sections adapted to be secured together and form vertical passages therefrom, a steam-drum secured to the ends of the uppermost header-section, a rear header consisting substantially of transverse central sections having openings between them for the passage of the products of combustion, and 35 vertical ends provided with closed heads resting upon, but not communicating with each other, water-tubes secured in the transverse portion of each front header-section and in the corresponding rear header-section in close proximity to each other, so as to form with the front and rear headers substantially fire-tight upper and lower return fire-flue walls, and downflow-pipes secured in the ends of each front header-section and in the ends of 40 the corresponding rear header-section at the sides of the boiler, substantially as and for the purpose set forth.

25 3. The combination in a tubulous steam-boiler, consisting substantially of tiers of water-tubes secured in front and rear headers, and a downflow-pipe, connecting said headers at each side of the boiler, corresponding to each tier of water-tubes, of feed-water pipes extending into the front ends of the 50 lower pair of downflow-pipes, and a mud-drum

communicating with the lower portion of the header at the rear of the boiler, substantially as and for the purpose set forth.

4. The combination in a tubulous steam-boiler, of a front header constructed of sections, each consisting substantially of a transverse shell, cylindrical ends on the ends of said shell, flanges on said cylindrical ends, whereby they can be secured together so as to form vertical passages up to the steam-drum secured to the topmost section, and a rear header constructed of sections, consisting substantially of transverse shells having cylindrical ends, the ends of which are closed and resting one upon another, substantially as and for the purpose set forth.

5. The combination in a tubulous steam-boiler, of a front header constructed of sections, each consisting substantially of a transverse shell inclined upward from the center toward the ends thereof, flanged cylindrical ends on said shells whereby said cylindrical ends can be secured together one above the other, so as to form continuous vertical passages up to a steam-drum secured to the uppermost section of the header, a rear header consisting substantially of a transverse shell inclined upward from the center toward the ends thereof, cylindrical ends on said shells, provided with closed heads, so that when the cylindrical end of one section is placed upon another there is no communication between them, and a tier of water-tubes secured between the shells and downflow-pipes between the cylindrical ends of the corresponding front and rear header-sections, substantially as and for the purpose set forth.

6. The combination in the header-sections of a tubulous steam-boiler, of transverse shells inclined upward from the center toward the ends thereof, and adapted to receive the ends of water-tubes secured therein, in close proximity to each other and vertical sections at each end of said shells adapted to be secured together and to a steam-drum, so as to form vertical passages at the sides of the boiler, from the ends of said shells to the steam-drum of the boiler, substantially as and for the purpose set forth.

In testimony whereof I affix my signature in presence of two witnesses.

LEONARD D. DAVIS.
